CENTER CONNECTION FOR STRUCTURAL ELEMENTS

Warren C. Weller, Camp Springs, Md., and Hugh B. Johnson, Arlington County, Va., assignors to the United States of America as represented by the Secretary of the Army

Application July 7, 1953, Serial No. 25,837

Term of patent 14 years

(Cl. D54—2)

To all whom it may concern:

Be it known that we, Warren C. Weller and Hugh B. Johnson, citizens of the United States, residing at Camp Springs, in the county of Prince Georges and State of Maryland, and in the county of Arlington and State of Virginia, respectively, have invented a new, original, and ornamental Design for a Center Connection for Structural Elements, of which the following is a specification, reference being had to the accompanying drawings, forming a part thereof.

In the drawings:

Figure 1 is a perspective view of a center connection for structural elements showing our new design;

Figure 2 is an end elevation thereof, looking from the right of Figure 1;

Figure 3 is a side elevation thereof looking from the left of Figure 1;

Figure 4 is a plan view thereof; and
Figure 5 is a bottom plan view thereof.

The fragmentary, broken line showing of structural elements in Figure 1 and Figure 2, is for illustration only.

We claim:

The ornamental design for a center connection for structural elements, substantially as shown and described.
